US00D579813S

(12) United States Design Patent
Calvani

(10) Patent No.: US D579,813 S
(45) Date of Patent: * Nov. 4, 2008

(54) WATCH BEZEL

(75) Inventor: Maria Cristina Calvani, Cologny (CH)

(73) Assignee: Rolex Watch U.S.A., Inc., New York, NY (US)

() Term: 14 Years

(21) Appl. No.: 29/274,273

(22) Filed: Apr. 10, 2007

(30) Foreign Application Priority Data

Oct. 31, 2006 (CH) 133286

(51) LOC (8) Cl. 10-07

(52) U.S. Cl. D10/128

(58) Field of Classification Search D10/30-39, D10/122-132; 368/276, 281, 282, 285, 294, 368/295, 308, 319, 223, 228, 232, 28, 21, 368/80

See application file for complete search history.
